IRONING MACHINE

James Gordon, Chicago, Ill.

Application August 3, 1940, Serial No. 350,198

7 Claims. (Cl. 38—60)

The ironing machine of the present invention is designed with a view of simplifying the construction as compared with ironing machines of the standard type now on the market, and with this end in view, mechanism of the type ordinarily employed for the purpose of moving the shoe toward and from the roll has been eliminated, so that during normal operations the shoe maintains constant pressure contact with the roll, which during the ironing operation is motor driven in a forward feeding direction, with provision, however, for reversing the motor drive temporarily in the event it becomes necessary to retract the article being ironed, so that the release of the article will be occasioned by the back feeding of the roll rather than by manual withdrawal as in the case of machines of standard type with which I am familiar.

The invention is further directed to the general structure of the machine and the means provided for mounting the operating parts in such a way as to adequately support the overhanging roll from the housing, leaving the outer end of the roll free from support, which is desirable in order to avoid unnecessary obstruction in the manipulation of the material being ironed.

The invention further relates to the general construction of the frame or housing portions of the machine with a view to the avoidance of the use of heavy castings or the like for the purpose of securing the necessary strength and rigidity without excessive weight, which is of primary importance in a device of this character intended for household use, and which must be easily portable as occasion may require.

The machine as a whole is mounted upon a base or platform, which may be supported upon a table top or the like, so that there is no necessity for housing the machine within a cabinet, although the machine may be so mounted if desired.

Further objects and details will appear from the description of the invention in conjunction with the accompanying drawings, wherein—

Figure 1 is a top or plan view of the machine as a whole;

Fig. 2 is an elevation mainly in section, with the roll and shoe partly broken away to reveal the mounting for the shoe;

Fig. 3 is a sectional elevation taken on line 3—3 of Fig. 2;

Fig. 4 is a diagram of the wiring arrangement for energizing the motor and heating coil;

Fig. 5 is a sectional detail of the switch mech-

anism for controlling the forward and reverse movements of the motor; and

Fig. 6 is a view of a portion of the switch mechanism taken on line 6—6 of Fig. 5.

The machine as a whole is mounted upon a rectangular base board 10 provided with feet 11 of rubber or the like, which enables the machine to be mounted upon a table top or other convenient support. The base board near its right hand end (Fig. 1) affords a mounting for a base frame 12, which as shown is of circular formation around its lower edge 13 and of generally conical formation above, with circumferential bulges or protuberances to afford the necessary space for the housing of certain of the operating parts and to give to the structure an attractive appearance.

The upper portion of the base frame 12 terminates in outwardly flaring marginal flanges 14 at the front and back of the walls of the base frame, which thus afford a cradle for the mounting of a drum shaped gear box 15, the cylindrical walls of which fit snugly within the cradle afforded by the base frame and may be secured thereto by spot welding or other convenient method of attachment. The inner face 16 of the gear box is offset to afford an inwardly projecting tapered extension 17 which terminates in an inturned flange 18 which assists in supporting the roll 19 in a manner presently to be described.

The inner face wall 16 of the gear box furnishes a support for the rim of a circular bridge plate 20 having a central aperture defined by a rearwardly extending flange 21. The rim of the bridge plate may be secured to the wall 16 by spot welding or other convenient means of attachment.

The outer margin 22 of the drum shaped gear box is offset to receive the inner rim of a drum shaped motor casing 23 which extends outwardly from the gear box to a considerable degree and serves to house a motor 24, the weight of which tends to a considerable degree to counterbalance the weight of the roll 19, so that the entire operating structure may be conveniently supported upon the cradle afforded by the base frame without additional means for supporting either the roll or the motor.

In order to hold the operating assembly firmly in position, a cylindrical strap or girdle 25 is provided which encircles the gear box and the edge of the motor housing, which latter is secured to the gear box by screws 26. The arrangement is one which permits the entire operating assembly to be slipped rearwardly within the girdle 25 which thus permits the motor housing

to be readily removed in order to secure access to the interior of the structure.

The inner end of the motor housing is closed by means of a circular cross wall 27 provided with a boss 28 which mounts a stub shaft 29 upon which is keyed a transmission spur gear 30 in mesh with a pinion 31 keyed to the motor shaft 32.

The inner circular flange 21 of the bridge plate 20 in conjunction with the flange 18 on the extension 17 afford a mounting for the inner end of a sleeve 33 which extends outwardly for substantially the full length of the ironing roll 19 and constitutes the sole means of support for the roll, which overhangs the base board of the machine. The sleeve 33 is non-rotatable, but affords a mounting for the rotation of the roll 19 which is provided with inner and outer end walls 34 and 35, both of which are provided with inturned flanges 36 carrying bushings 37 which rotate upon the sleeve as a bearing surface.

The roll is actuated by the rotation of a shaft 38 which is housed within the sleeve 33 and terminates in a reduced threaded stub 39 entered through a cap plate 40 which is spot welded or otherwise secured to the end wall 35 which is clamped to the edge of the shaft 38 by a nut 41. Thus the rotation of the shaft 38 imparts rotation to the roll journaled upon the rigid sleeve 33, which in turn is firmly anchored at its inner end within the frame of the machine.

The stub shaft 29 has keyed thereon a pinion 42 which meshes with an internal gear 43 mounted within the flanged rim of a hub plate 44 which mounts a stub shaft 45 carrying a freely mounted orbital pinion 46. The pinion is in mesh with two gears, a fixedly positioned gear 47 rigidly mounted upon the inner end of the fixed sleeve 33, and a movable gear 48 keyed to the shaft 38. One of the two gears has one more tooth than the other, so that with each revolution of the orbital pinion 46 the roll shaft will be advanced one tooth.

The arrangement heretofore described constitutes a reduction gear train which includes the motor shaft pinion 31, the intermediate transmission gear 30, and hub plate 44, and through the planetary gear 46 and movable gear 48 to the roll shaft. Although the above described reduction gear arrangement affords a satisfactory means for driving the ironing roll, it will be understood that it serves merely for purposes of illustration of an operative assembly and that any other convenient or satisfactory arrangement may be employed in lieu thereof.

The shoe 49 is of the usual arcuate formation and extends from end to end of the roll and encloses a heating element 50 (Fig. 4) of any suitable character. The shoe normally maintains constant spring pressure contact with the roll, although provision is made for the manual release of the shoe as occasion may require. The shoe is provided with rearwardly extending ears 51 which embrace the inner end of a pressure head 52 to which the ears are pivoted upon a pintle 53. The pressure head is provided with an upwardly extending lever arm 54 terminating in a handle knob 55. The pressure head is pivoted upon a pintle 56 entered through the upper side walls 57 of a channel mounting 58 which is pivoted near its center upon a pivot pin 59 entered through the side walls of a standard 60 which springs upwardly from the base plate 18.

The lower end of the mounting 58 is beveled as at 61, and bears against the upper end of a lever plate 62 pivoted at its lower end upon a pivot 63. A spring 64 serves to exert an outward

thrust against the lever plate which in turn tends to force the lower end of the channel mounting outwardly, which thus imparts an inward thrust to the upper end of the channel mounting and the pressure head and shoe carried thereby. When the shoe is in compressed relation with the roll, the center of the pivot 53 lies slightly below the center line of operation between the roll and the pivot 56, so that in order to release the shoe, sufficient manual pressure must be exerted to move the parts beyond the dead center line, after which the shoe may be swung outwardly to the limit of its movement.

A reversing motor is employed, which is wired in conformity with the diagram shown in Fig. 4, with a view of operating in the following manner: With the operating switch thrown to the first position, the motor will be energized in a forward direction and the ironing roll will advance to feed the material under the pressure of the shoe until such time as the operator may desire to reverse the feeding movement in order to feed back the material in cases where cramping or binding may occur, or a readjustment of the material becomes necessary to avoid wrinkling or the like. In such event the operator moves the switch to the second position, which reverses the current flow through the motor, with provision, however, for automatically stopping the reverse movement after fractional reverse rotation of the ironing roll has occurred. This serves to release the material and automatically stop the machine until the material has been readjusted in position to continue the normal operation. For this purpose the switch mechanism shown in Figs. 5 and 6 may be employed, although it will be understood that the specific arrangement shown serves merely for purposes of illustration and that other suitable types of switch mechanism may be employed for a like purpose.

The switch elements as shown are mounted upon a shaft 65, the outer end of which is entered into a socket head 66 journaled through a boss 67 and carrying a handle 68; the inner end of the shaft 65 is journaled within a bracket 69 upstanding from the base of the machine. The bracket carries an insulating block 70 which mounts the contacts 71 and 72 in circuit with the line wires 73 and 74 respectively. The block 70 also mounts contacts 75 and 76, 77 and 78. The contacts 75 and 76 are in circuit through wires 79 and 80 with the heating element 50, and also in circuit through wires 81 and 82 with the motor 24. The contacts 77 and 78 are in circuit through wires 83 and 84 respectively with the circuit wires 79 and 80.

The shaft 65 is entered through the insulating block 70 which is recessed to receive the reduced end of a movable insulating block 85 which is freely mounted upon the shaft 65 and carries brush contacts 86 and 87 adapted to bridge over the spaces between two adjacent fixed contacts. The movable insulating block 85 on its outer face carries a disk 88 provided on its periphery with three elevations 89 each of which terminates in an abrupt forward edge 90 adapted to be contacted by the upper end of a spring stop 91.

The shaft 65 also has rigidly mounted thereon a lever 92, the upper end of which carries a pawl 93 adapted to engage notches 94 in the edge of a disk 95 carried by a hub 96 freely mounted upon the shaft. The lower end of the lever 92 is connected by a pin and slot connection with the plunger 97 of a dash pot 98 for retarding the return of the lever in a manner presently to be described.

The lever 92 at a point adjacent the stop 91 is provided with a hump 99 which is adapted to abut against the stop, and the return of the lever is effected through the tension of a spring 100. The notched disk 95 is connected with the disk 88 through the medium of a coil spring 101, the ends of which are entered into the respective parts, and in order to prevent backward movement of the rotating parts, a ratchet 102 coacting with a dog 103 is provided.

In order to insure the completion of movements initiated by the operating handle 68, the disk 104 is rigidly mounted upon the shaft 65 and provided with a row of teeth 105, which terminates at each end in a clearance space 106. The teeth 15 coact with a spring backed dog 107 so disposed that, after the first tooth of the series has passed the dog, it will be impossible to reverse the movement until the terminal clearance space is reached, which permits reversal of the position 20 of the dog.

Operation

In operation, with the brush contacts 86 and 87 occupying the dotted line position indicated by A in the diagram, the circuit will be broken and the motor deenergized. If the operating handle be swung sufficiently to bring the brush contacts into the first operating position indicated by B, the contacts 71 and 78, and also 72 and 77, will be bridged, and a forwardly energizing current will flow from the line wire 74 through the contacts 72, 87 and 77, and wires 83, 79 and 81 to the motor, and thence through the wires 82, 80 and 84, contacts 78, 87 and 71, to the line wire 73. The ironing roll will thus be rotated in a forward direction.

The movement imparted to the shaft 65 by the handle 68 serves to rotate the lever 92 carrying the dog 93, which latter engages one of the notches in the disk 95, but as soon as the lever arm 92 begins to rotate, its lower end is retracted away from the spring stop 91, so that the upper end of the latter moves into position to engage the abrupt end 90 of the stop elevation 89, which exhausts the movement imparted by the handle which, when released, will restore to its normal position, the movement, however, being retarded by the action of the dash pot. However, after the first handle movement, the parts will remain in the dotted line position shown in Fig. 6 and with the contacts in the position B previously described, and with the motor operating to forwardly rotate the ironing roll.

If in these circumstances it becomes necessary to suddenly reverse the movement to prevent congestion of the material, or for any other reason, a second movement of the handle will carry the contacts to the reversing position C in the diagram. As the handle starts its movement, the disk 88 will begin to advance from the dotted line position shown in Fig. 6, and concurrently the lower end of the lever 92 will be retracted to release the spring stop 91, which, however, will ride upon the edge of the advancing elevation 89, so as to permit the disk 88 to advance to the reversing position C, but before this position is reached, the spring stop will snap inwardly into position to encounter the next step and thus arrest the stop disk 88 and the movable insulating block 85 with its contacts, while a continued movement of the handle will impart further rotation to the notched disk 95, so that tension will be stored up in the spring 101 during the terminal movement of the handle.

After the handle has been released, the lever arm 92, under the tension of the spring 100, will begin to move back at a retarded rate and during the intended time interval provided by the dash pot, with the result that the contacts will maintain the reversing position for a timed interval and until the lever bar 92 restores sufficiently to kick back the spring stop 91, which will release the disk 88 and allow the same with the contacts to snap back to the original off position A in the diagram.

During the reversing position C, the current will flow through the line wire 74, fixed contact 72, movable contact 87, fixed contact 76, wires 80 and 82, to the motor, and thence through wires 81 and 79, fixed contact 75, movable contact 87, fixed contact 71, to the line wire 73. After the conclusion of the reversing movement, the movable contacts will assume the position indicated by A, and the motor will be deenergized in preparation for a further handle movement to start the motor in the advance feeding direction.

The arrangement of the rotating switch elements is one which is permitted in one direction only, so that there can be no possibility of mal-adjustment during the operation of the machine. To stop the motor, therefore, it is merely necessary to throw the handle to the reversing position, which will momentarily reverse the rotation of the roll and automatically bring the machine to a stop after the time interval has been exhausted. The reverse movement, therefore, is one of sufficient amplitude to feed back the material to the necessary extent to permit the operator, with the roll at rest, to make necessary readjustments, and thereafter, by moving the handle, the machine will be started. It is unnecessary for the operator to pay any attention to the stopping of the reverse movement, which occurs automatically.

The invention as a whole differs radically from ironing machines of the conventional type, in that it positively feeds back the material when conditions require, and therefore does not necessitate any release of the shoe pressure against the roll, which remains constant at all times save in case of emergency in which a manual reversing is permitted by the operation of the handle 54.

The general structure of the machine is one which permits the frame to be constructed of plate metal by stamping or spinning, and completely avoids the use of castings, so that full strength and rigidity will be insured with a minimum of weight, and by eliminating all power driven mechanism for operating the shoe, the mechanical structure of the machine is greatly simplified and the cost reduced to a minimum.

Although the general structure of the machine and the arrangement of all of the operating parts have been described in full detail, it will be understood that the arrangement shown serves merely for purposes of illustration and that numerous changes in detail can be made without departing from the spirit of the invention.

I claim:

1. In an ironing machine, the combination of an ironing roll, a reversing motor and connections between the roll and the motor for imparting forward or reverse rotation to the roll, a shoe adapted to maintain pressure against the roll during both forward and reverse feeding movements, and a switch mechanism and electrical connections adapted when the switch is moved to one position to constantly energize the motor for movement in a forward feeding direction and

when moved to a second position to energize the motor in the reverse feeding direction, and automatic means for actuating the switch to move the same to open circuit position after a limited period of reverse motor movement.

2. In an ironing machine, the combination of a supporting member, a housing balanced upon said supporting member, a motor and motor casing rigidly connected with said housing and projecting rearwardly from the point of support therefor, the housing being provided with an extension inwardly projecting to a substantial degree beyond the point of support for the housing, a fixed supporting sleeve having its rear end entered into and supported by the housing and additionally supported at its intermediate point by the extension therefrom and inwardly projecting from said intermediate point of support and otherwise unsupported, an ironing roll journaled upon the inwardly projecting portion of the sleeve, an operating shaft extending through the sleeve and connected at its outer end to the roll for rotating the same, the mechanisms extending inwardly from the supporting member being counterbalanced by the motor and motor casing, a shoe adapted to contact the roll, and driving connections located within the housing and adapted to transmit power from the motor to the shaft.

3. In an ironing machine, the combination of a supporting member, a housing balanced upon said supporting member, a motor and motor casing rigidly connected with said housing and projecting rearwardly from the point of support therefor, the housing being provided with an extension inwardly projecting to a substantial degree beyond the point of support for the housing, a fixed supporting sleeve having its rear end entered into and supported by the housing and additionally supported at an intermediate point by the extension therefrom and inwardly projecting from said intermediate point of support and otherwise unsupported, an ironing roll journaled upon the inwardly projecting portion of the sleeve, an operating shaft extending through the sleeve and connected at its outer end to the roll for rotating the same, the mechanisms extending inwardly from the supporting member being counterbalanced by the motor and motor casing, a shoe normally having constant contact with the roll, driving connections located within the housing and adapted to transmit power from the motor to the shaft, and switch mechanism and electrical connections for energizing the motor to operate either in the forward or reverse direction.

4. In an ironing machine, the combination of a supporting member, a housing balanced upon said supporting member, a motor and motor casing connected with said housing and projecting rearwardly from the point of support therefor, the housing being provided with an extension inwardly projecting to a substantial degree beyond the point of support for the housing, a supporting sleeve entered into and supported at its end by the housing and additionally supported by the extension therefrom, an ironing roll journaled upon the sleeve, an operating shaft extending through the sleeve and connected at its outer end to the roll for rotating the same, a shoe adapted to contact the roll, driving connections located

within the housing and adapted to transmit power from the motor to the shaft, a switch mechanism and electrical connections adapted when the switch is moved to one position to constantly energize the motor for movement in a forward feeding direction and when moved to a second position to energize the motor in the reverse feeding direction, and automatic means for actuating the switch to move the same to open circuit position after a limited period of reverse motor movement.

5. In an ironing machine, the combination of an elongated base member, a base frame fixedly mounted thereon and extending upwardly therefrom and configured at its upper end to provide a cradle, a housing mounted within said cradle and provided on its side wall with an extension projecting inwardly beyond the point of support afforded by the cradle, the housing being provided on its interior with a bridge plate, a fixed sleeve outwardly extending from the housing and supported at its inner end within the bridge plate and supported at an intermediate point by the extension, an ironing roll journaled upon the sleeve and overhanging the base member, a roll shaft extending through the sleeve and connected at its outer end with the ironing roll, a motor casing fixedly secured to and supported by the housing and extending outwardly therefrom beyond the cradle on the side opposite to the roll, a motor within the casing serving in part to counterbalance the weight of the roll, a reducing train located within the housing for imparting rotation from the motor to the roll shaft, and a shoe coacting with the roll.

6. In an ironing machine, the combination of an ironing roll, a reversing motor and connections for rotating the roll either in a forward or reverse direction, a shoe adapted normally to apply pressure to the roll when rotating in either direction, and a switch device and electrical connections with the motor, the switch device including means for closing the forward energizing circuit when moved to the first position, and adapted when moved from the first to the second position to close the reversely energizing circuit and to store up power for thereafter moving the switch to open position, and trip means for releasing the switch from the second position of adjustment after the lapse of a predetermined period of time to permit the automatic movement of the switch to open position to stop the limited reverse rotation of the roll.

7. In an ironing machine, the combination of a rotatable roll together with a shoe yieldingly associated therewith, reversible means in train with the roll for rotating the same in either forward or reverse direction, and adjustable control means and connections therefrom to the reversible power-applying means, the control means in one position of adjustment establishing and maintaining unlimited forward movement of the power-applying means with consequent forward movement of the roll, and the control means in another position of adjustment establishing and maintaining for a limited period only, a reverse movement of the power means with cessation of movement thereafter with consequent reverse movement of the roll and stopping thereafter.

JAMES GORDON.
